US00D811056S

(12) **United States Design Patent** (10) Patent No.: **US D811,056 S**
(45) Date of Patent: ** *Feb. 27, 2018

(54) **BALL CAP WITH CIRCULAR-SHAPED ELECTRONIC DISPLAY SCREEN**

(71) Applicant: **Andrew Zenoff**, San Anselmo, CA (US)

(72) Inventor: **Andrew Zenoff**, San Anselmo, CA (US)

(73) Assignee: **Beam Authentic, LLC**, San Anselmo, CA (US)

(*) Notice: This patent is subject to a terminal disclaimer.

(**) Term: **14 Years**

(21) Appl. No.: **29/499,864**

(22) Filed: **Aug. 19, 2014**

(51) LOC (11) Cl. **02-03**

(52) U.S. Cl.

USPC **D2/882**

(57) **CLAIM**

The ornamental design for a ball cap with circular-shaped electronic display screen, as shown.

DESCRIPTION

FIG. 1 shows a perspective view of a ball cap with circular-shaped electronic display screen;

FIG. 2 shows a front elevation view of the ball cap with circular-shaped electronic display screen;

FIG. 3 shows a side elevation view of the ball cap with circular-shaped electronic display screen; and,

FIG. 4 shows a top plan view of the ball cap with circular-shaped electronic display screen.

1 Claim, 2 Drawing Sheets
